(57) **CLAIM**

The ornamental design for an orthopedic pillow for sleeping, as shown and described.

DESCRIPTION

1. Orthopedic pillow for sleeping

1.1 : Perspective

1.2 : Front

1.3 : Back

1.4 : Top

1.5 : Left

Fig. 1.1 is a perspective view of the orthopedic pillow for sleeping; fig. 1.2 is a front view thereof; fig. 1.3 is a back view thereof; fig. 1.4 is a top view thereof; and fig. 1.5 is a left view thereof.
